CLAIM

The ornamental design for a face plate for a printed circuit board, as shown and described.

DESCRIPTION

FIG. 1 is a front elevational view of a face plate for a printed circuit board showing my new design, with the rear forming no part of the claimed design and the broken lines showing a printed circuit board being for illustrative purposes only and forming no part of the claimed design;

FIG. 2 is a side elevational view as seen from the left of FIG. 1;

FIG. 3 is an elevational view of the opposite side thereof; and,

FIG. 4 is a perspective view thereof, the bottom edge being a mirror image of the top edge shown.
